ASSIGNORS TO MASTER CARBURETER COMPANY, OF LOS ANGELES, CALIFORNIA, A CORPORATION OF CALIFORNIA.

DOUBLE-FUEL CARBURETER.

1,183,221.

Specification of Letters Patent. Patented May 16, 1916.

Application filed May 4, 1914. Serial No. 836,051.

To all whom it may concern:

Be it known that we, HARRY A. MILLER and FRANK M. ADAMSON, both citizens of the United States, residing at Los Angeles, 5 in the county of Los Angeles and State of California, have invented a new and useful Double-Fuel Carbureter, of which the following is a specification.

This invention relates to a carbureter designed for using two fuels, whereby in starting the engine a lighter or more volatile fuel may be employed, and after the engine has been started, another fuel which may be less volatile, heavier or less expensive, may be utilized, and the main object of the present invention is to so construct the carbureter that the use of these two fuels will be entirely automatic. Thus, in starting, the operator will adjust the throttle in 10 the usual manner, as though he were using a carbureter of the ordinary construction, in which a single fuel is employed, and this adjustment in the present invention will automatically operate to restrict the fuel 15 used at such time to the lighter and more volatile starting fuel, as, for example, gasoline; after the engine has started, and as the operator opens the throttle, this adjustment will automatically operate to supply 20 the other operating fuel. In the present embodiment after the regular running fuel is being supplied, the supply of starting fuel still continues, but this amount of starting fuel is of relatively such small proportion 25 compared with the regular running fuel as to be practically negligible.

Referring to the drawings: Figure 1 is a side elevation of the carbureter with a portion of the float chamber being in section. Fig. 2 is a section on line x^2-x^2 , Fig. 1. Fig. 3 is a plan view. Fig. 4 is a plan view of the float chamber with the cover removed. Fig. 5 is a view looking toward the bottom 40 of one of the float chambers with the lower float chamber cap removed and a part of the screen broken away. Fig. 6 is a section on line x^6-x^6 , Fig. 3. Fig. 7 is a section on line x^7-x^7 , Fig. 6. Fig. 8 is a section on line x^8-x^8 , Fig. 6, Fig. 9 is a section 45 on line x^9-x^9 , Fig. 6. Fig. 10 is a section on line x^{10} , Fig. 6. Fig. 11 is a section on line $x^{11}-x^{11}$, Fig. 10. Fig. 12 is a plan view of the throttle. Fig. 13 is a view simi-

lar to Fig. 12 showing the throttle slightly turned to the left.

The construction of the present carbureter, except for the float chamber is substantially similar both in general and in detail to the construction shown in a former application of ours filed February 10, 1914, Serial No. 817,779.

The carbureter comprises a central barrel portion 1, in which the throttle 2 is revolvably mounted and over which is the neck 3, through which the mixture is discharged to the induction pipe, not shown. Below the barrel 1 is a distributor chamber 4 containing a distributor 5, the distributor 5 being in the present embodiment in the form of a thin flat elongated body which extends through the distributor chamber 4 dividing the chamber into two air passages 6 and 7, air being supplied to the distributor chamber from an air inlet 8, which has an open end 9 and may also have several segmental side openings 10, as indicated by dotted line in Fig. 3. The openings 10 may be controlled by an external revoluble sleeve 11, having segmental openings 12 adapted to be moved into register with the openings 10 and adjustably secured in the position set by a screw 13.

The throttle 2 is mounted on a shaft 14 journaled in the ends of the barrel 1, and has a central passage 15 with curvilinear edge 16, as clearly shown in Figs. 12 and 13, which at one end is so abruptly curved as to form the side wall of a transverse narrow annular passage 17. The passage 17 is segmental and does not extend entirely around the throttle, there being solid portions 18 on intervening segments of the throttle. An arm 19 is secured to the shaft 14 for operating the throttle. The distributor 5 is provided with a single passage 19' in its lower portion, with which communicate a series of vertical passages 20, the upper wall of the distributor having a series of small perforations 21, which communicate with the respective passages 20. The upper edge 22 of the distributor is slightly below the face of the solid portion of the throttle, for example, about $\frac{1}{2}$ of an inch space being allowed, while at the extreme right hand side, as shown in Fig. 7, is a single 100 perforation 23 in a raised edge portion 24,

which lies above and close to the throttle. A partition 25 is arranged in the distributor chamber to form separate air passages 6' and 7' for supplying air for the single perforation 23. A damper 26 is mounted on a shaft 27 and located in the air passage 7 to control the amount of air allowed to pass through the passage 7. The normal air enters through the passage 6.

10 The two different fuels are supplied to the distributor at the opposite ends of the distributor, which protrude from the chamber 4, and which respectively communicate with passages 28 and 28', which lead respectively to hollow screw plugs 29 and 29', which project into and communicate with float chambers 30 and 30'. Screens 31 and 31' are secured to the ends of the respective screw plugs 29 and 29' to prevent impurities in the fuels from entering the passages leading to the distributor. Secured to the bottom of each float chamber is a cap 32 and 32' which form sub-chambers 33 and 33', to which the liquid fuels are supplied through nipples 34 and 34'. In each sub-chamber is a screen 35 to check passage of impurities, and over which screen 35 are passages 36 leading to a needle valve seat 37. 38 is a drain passage normally closed by screw plug 39. Each valve seat 37 is controlled by needle valve 40, and freely slideable on each needle valve 40 is a float 41 which is adapted to operate levers 42, which engage a grooved collar 43 on the associated needle valve 40 so that as the float rises it causes a closing movement of the needle valve, and in this way the amount of fuel in each float chamber is automatically controlled and kept at a substantially definite level therein. The two float chambers are preferably formed as a single casting, and have a single top cover 44 which may be secured in place by thumb-nut 45.

In operation the starting fuel is conducted to the float chamber 30, and the running fuel is fed to the float chamber 30'. When the operator turns the throttle to starting position the solid portions of the throttle cover the perforations 21, while the passage 50 17 of the throttle opens communication with the single perforation 23 so that the entire suction of the motor is confined to the single perforation 23, with the result that the starting fuel which enters the associated end 55 of the distributor is sucked into the carbureter to the exclusion of the other fuel. After the motor starts and the throttle is turned further to move its curvilinear edge 16 so as to uncover some of the perforations 60 21, the suction then is applied to the perforations 21, and the regular running fuel is drawn through the perforations 21. As additional perforations 21 are uncovered by turning the throttle further, more fuel is 65 admitted, although after the ports 21 have

been opened to admit the regular running fuel and port 23 still remains open, the amount of fuel permitted to enter through port 23 is so slight compared to the amount which enters through the ports 21 as to be practically negligible. It will be noted that the admission of the two fuels is entirely automatic, and that no thought on the part of the operator is required, the starting fuel being automatically supplied when he adjusts the throttle for starting, and the regular running fuel being supplied when he adjusts the throttle into any of the regular running positions. It is thus possible to employ a good starting fuel, such as gasoline, 75 for the starting of the motor, and to employ a cheaper fuel, such, for example, as distillate, for the regular running fuel.

What we claim is:

1. In a carbureter, a distributor provided with separate aligned parallel fuel passages, a single rotary valve for closing certain of said passages to confine the flow of fuel to a certain passage, said valve operating externally of the distributor and extending longitudinally thereof, means for supplying one fuel to said certain passage, and means for supplying another fuel to another passage. 85

2. In a carbureter, a distributor having passages for running fuel, and a passage for starting fuel, a float chamber in communication with the first named passages for supplying one kind of fuel to said passages, another float chamber in communication with the starting passage for supplying a starting fuel to the latter passage, and a valve for closing all of said passages the valve being also adapted to close the first named passages to cause only starting fuel to pass through the starting passage. 95

3. In a carbureter, a distributor having passages for running fuel, and a passage for starting fuel, a float chamber in communication with the first named passages for supplying one kind of fuel to said passages, another float chamber in communication with the starting passage for supplying a starting fuel to the latter passage, a throttle valve having a curvilinear edge located adjacent the distributor passages, and having a narrow passage for confining suction to the said starting passage. 110

4. In a carbureter, a distributor chamber, a distributor in said chamber dividing the same into two air passages for normal air and auxiliary air, the ends of said distributor extending through the walls of the distributor chamber, two float valve chambers with passages leading from the respective float valve chambers to the opposite ends of the distributor, the distributor having a passage for delivering fuel from one of said float chambers, and having a series of passages for delivering fuel from the other float chamber, and a throttle above said distributor. 125

ter for covering definite passages in the distributor.

5. In a carbureter, a distributor having a running fuel passage and a starting fuel passage, means to supply one kind of fuel to the running fuel passage, means to supply another kind of fuel to the starting fuel passage, and a single valve closing the running fuel passage when the starting fuel 10 passage is open and opening the starting fuel passage when the running fuel passage is open.

6. In a carbureter, a distributor having a running fuel passage and a starting fuel 15 passage, means to supply one fuel to one of

the passages, means to supply another fuel to another of the passages, and a single valve closing the running fuel passage and opening the starting fuel passage when in one position and means to move the valve 20 into different positions.

In testimony whereof, we have hereunto set our hands at Los Angeles, California, this 8th day of April, 1914.

HARRY A. MILLER.
FRANK M. ADAMSON.
